LIFEBOAT PROPELLING MECHANISM

Clarence W. Allen, San Francisco, Calif.

Application February 24, 1936, Serial No. 65,452

6 Claims. (Cl. 115—24)

This invention relates to life-boats and particularly to a propelling mechanism therefor, the present invention being a continuation in part of my co-pending application entitled 5 "Propelling mechanism" filed November 28th, 1934, Serial Number 755,190.

The object of the present invention is generally to improve and simplify the construction and operation of propelling mechanisms of the 10 character described; to provide a driving mechanism for actuating the propelling mechanism which may be attached to the seats of a boat without changing or re-arranging the seats or the air tanks placed alongside or under the 15 seats; to provide a driving mechanism which can not be blocked or disabled by the action of ice and frost, etc.; to provide a driving mechanism which will avoid the transmission of strain to the bottom of the boat and thereby tend to 20 strain or open the seams; to provide a driving mechanism which extends substantially throughout the length of the boat and which is so arranged in position that three rows of people can 25 conveniently and efficiently actuate the same, in fact, permit at least double the number of 30 people in the boat to be actively engaged in the propulsion of the boat when comparison is made with oars; to provide a combination propelling and driving mechanism which is capable of being 35 set at neutral, ahead, or reverse; and, further, to provide a single lever control within convenient reach of the officer in charge of the boat for actuating the setting mechanism for neutral, ahead, or reverse.

35 The invention is shown by way of illustration in the accompanying drawings, in which—

Fig. 1 is an enlarged longitudinal vertical section of a portion of the boat, said section showing the propelling mechanism and the driving 40 mechanism whereby it is actuated;

Fig. 2 is a cross section taken on line II—II of Fig. 1;

Fig. 3 is a cross section taken on line III—III of Fig. 1;

45 Fig. 4 is a cross section taken on line IV—IV of Fig. 1;

Fig. 5 is an enlarged longitudinal section of the propelling mechanism and the mechanism whereby ahead drive, neutral or reverse is attained;

50 Fig. 6 is a plan view of the life-boat showing the installation of the driving and propelling mechanism;

Fig. 7 is a perspective diagrammatic view showing the manner in which the driving mechanism 55 and the propelling mechanism are connected.

Referring to the drawings in detail, and particularly Figs. 1 and 6, A indicates a life-boat of standard construction and B the seats extending crosswise thereof. The seats serve two functions, first that of seating the crew and passengers, 5 and secondly, that of a support for the driving mechanism generally indicated at C.

The driving mechanism consists of a pair of rods 2 and 2^a which extend longitudinally of the boat and which are spaced apart a sufficient distance to permit one person on each set to sit between the rods. The rods are provided with a series of handles 3 and 3^a by which the rods are grasped when the boat is to be propelled and the rods are guided and supported in eye bolts 4 and 15 5 secured to the respective seats.

In addition to the driving mechanism, a propelling mechanism is employed. This mechanism is mounted within the housing D. Suitably secured in the boat and adjacent the rear end 10 thereof a shaft 6 is journaled in and extends through the rear end of the housing and is connected through a universal joint, or the like, 7 with a propeller shaft 8 which extends through a stern bearing and carries a suitable type of 20 25 propeller 9. The propelling mechanism is carried by the shaft 6 and is disposed within and completely enclosed by the housing D. The propelling mechanism is identical to the propelling mechanism disclosed in my copending application with the exception, to wit, the propelling mechanism here disclosed is provided with means for setting it in neutral or reverse in addition to the ahead drive; a reverse and neutral being 30 an essential feature of a life-boat drive. 35

In order that the neutral and reverse action can be clearly understood a brief description of the propelling mechanism will be submitted. Referring to Figs. 1 to 5, inclusive, it will be noted that the shaft 6 carried two drums 10 and 40

11. These drums are placed end for end longitudinally of the shaft and are separated by a disc 12, which is keyed to the shaft so as to rotate in unison therewith. Formed on the ends of the drum adjacent the disc 12 are ratchet gears 13 45 and pivotally mounted on each side of the disc and adapted to engage the ratchet gears are pawls 14, see Fig. 2. Surrounding the disc is a ring 16 and extending inwardly from said ring and into slots formed in the disc 12 are a pair 50 of cam members 17 and 18. The exterior surface of the ring 16 is provided with a pair of annular flanges forming a groove 19 in the center of which extends a fork 20 of a shaft rod 21, said rod being connected at one end with a lever 22 55

whereby the ring may be shifted laterally of the disc 12. Cams 17 and 18 are so shaped that during lateral movement thereof in one direction rocker extensions 23 on the respective pawls 5 will be engaged by the cams and both pairs of pawls on opposite sides of the disc 12 will be lifted free of the ratchet gears and the propelling mechanism will assume a neutral position.

If the ring 16 and the cams 17 and 18 assume the position shown in Fig. 5, only one pawl of 10 each pair will be engaged and held free of the cooperating ratchet gear, as plainly shown in Fig. 2, hence if the drums 10 and 11 are rotated a drive will be transmitted from the ratchet gears 15 through the engaging set of pawls to the disc 12 and as this is keyed to the shaft 6 rotary motion in one direction will be transmitted from shaft 6 to the propeller shaft 8. On the other hand, if the shifting ring and the cams 17 and 18 are 20 moved to a position opposite to that shown in Fig. 5 the pawls, which previously engaged the ratchet gears, will be released and will be pressed into engagement with their respective ratchet gears by means of the spring 24 and the pawls 25 which previously engaged, will be raised to disengage the ratchet gears. Hence, during rotation of the drums 10 and 11 rotary motion will 30 be transmitted to the disc 12 and the shafts 6 and 8 in a reverse direction and when ring 16 and the cams 17 and 18 are moved at a midway position neutral will be attained, as all the pawls will be held out of engagement. Lever 22 carries 35 a pawl 25 which cooperates with the notched segment or leg 26. Lever 22 is also provided with a hand grip which is connected with the pawl 25 and lever 22 may thus be swung about its pivot and secured in any one of the three notches shown, notch 26 being the one engaged when an ahead drive is desired. The middle notch is engaged when neutral position is assumed and the notch 27 when reverse is desired.

When the driving mechanism is in operation rods 2 and 2^a will be reciprocated in opposition to each other and means are provided for transmitting the reciprocal motion of the rods to rotate the drums 10 and 11 in opposite directions. This is accomplished as follows.

Formed on the exterior surface of each drum is a helical groove 29. The groove on the drum 50 10 is pitched in one direction and the groove on the drum 11 in the opposite direction as clearly shown in Fig. 5. A pair of cables 30 and 31 are anchored at one end, as shown at 32 and 33, to the eye bolts indicated at 5. These cables pass 55 over pulleys 34 secured to the respective rods 2 and 2^a and then over guide pulleys 35 secured under the seat. The opposite end of cable 31 is suitably secured to the drum and wound around the helical groove formed on the surface of the 60 drum 10 and then around and anchored thereto. Cable 30 is similarly wound around the groove formed in the exterior of the drum 11 and also anchored. The second cable is passed over an idler pulley 36 and the two ends, indicated at 37 65 and 38, are wound around the respective drums and anchored thereto. The windings of the cables 37 and 38 occupy the inner half of each drum and the windings of the cables 30 and 31 occupy the outer half of each drum. It should 70 also be noted that the cables 37 and 38 are wound in one direction about the respective drums and so are the cables 30 and 31 but in a direction opposite to the cables 37 and 38; but in view of the fact that the pitch of the helical grooves on the 75 respective drums is in opposition to each other

the cables 30 and 31 will transmit a reverse motion to each other and thereby cause one drum to rotate in one direction and the other drum to rotate in the opposite direction when a reciprocal movement is transmitted thereto from the 5 driving rods 2 and 2^a. A fourth cable is shown at 48 in Fig. 7. This passes over guide pulleys 41 secured on an adjacent seat and the ends of the cable are anchored to the respective rods, as shown at 42. This cable attachment is essential 10 as it insures reciprocal movement of the rods 2 and 2^a in opposition to each other and in unison, and it is also essential for the simple reason that the power transmitted to the rods through the crew or passengers pulling thereon is alternately transmitted through the cable 49 to one rod or another and the cables 30 and 31 connected therewith to rotate whichever drum happens to be the driving drum. For instance, if rod 2 is being pulled in the direction of arrow a, see Fig. 20 15 7, rod 2^a will be traveling in the reverse direction, or that indicated by arrow b. That is, the crew or passengers on one side will be pulling on the rod 2, while they will be pushing on the rod 2^a, but the push exerted on the rod 2^a will be exerted as a pull on the rod 2 as motion is transmitted to the rod 2 from the rod 2^a through the cable 48, hence all combined power or effort applied to the rods is transmitted alternately from one rod to the other and the rod to which the 25 power is transmitted is in turn submitted to the drum which is transmitting the drive.

In view of the fact that the rods 2 and 2^a are supported and guided by the eye bolts 5 only means must be provided for preventing rotation 30 of the rods as it is always desirable to maintain the handles in an up-raised position as shown to prevent rotation of the rods and also to maintain the handles 3 and 3^a in the proper position at all times. A pair of guide rods are employed as 40 shown at 45 in Fig. 1. A bracket 47 is extended from one of the handles into the rod 45 and slides thereon, there being one bracket 47 for each rod. In fact, the brackets 47 are nothing more or less than a continuation of the brackets supporting the pulleys 34 but inasmuch as they straddle or engage the rods 48 disposed below the seats, rotation of the rods 2 and 2^a is prevented. The ends of the rods extend beyond both the bow and the stern seat and they may be passed either under and over the same. In Fig. 1 an offset is 50 shown in the rods, as indicated at 2^b. Where said rods pass beneath the stern seat 59 an eye bolt 51 is provided to guide the end of the rod, the construction being the same as far as the 55 bow seat is concerned. On the other hand if it is desirable to bring the rod over the seat the eye bolt may be placed on top as shown by dotted lines. The rod may be extended therethrough, as shown by dotted lines in Fig. 1, the same being 60 true of the bow seat.

In actual practice when a life-boat is filled with crew and passengers one person on each seat will sit between the rods and one person will sit on the outer side of each rod; thus, there 65 are three rows of people engaged in the propulsion of the boat. The center row of individuals will grasp the upright portions of the handles, indicated at 3, while the rows of individuals sitting outside of the rods, or between the gunwales and the rods, will grasp the horizontally extending handle sections 3^a. With the number of handles here shown, it is possible for twenty-one people to be actively engaged in the propulsion 70 of the boat. The boat shown is a six seater 75

and could not use more than twelve oars. Where oars are employed they would be limited to twelve men rowing but with the driving mechanism here shown practically twice the number can be employed and obviously the exertion need not be as great. People rowing, whether it be crew or passengers, may face either forward or rearwardly, this making no difference in view of the fact that when they grasp the handle they are pulling when the rods are traveling in one direction and they are pushing when the rods are traveling in the opposite direction.

The propelling mechanism being completely enclosed by the housing B is always safe against the entrance of rain or water as it is tight and, in fact, may be partially filled with lubricant; hence any danger of freezing or blocking the propelling mechanism is entirely avoided. On the other hand, the driving mechanism, to wit, the rods and the cables connected therewith may be covered with spray during cold weather and as such will freeze up but if they are frozen up and it is necessary to use the boats the ice, which is formed between the rods and the eye bolts, can be almost instantly released by merely tapping the rods and pulleys. That is, a certain amount of play is provided between the rods and the eye bolts, hence a slight shock or tap of any nature, even with the hand, is sufficient to break any ice formation and if any ice is left it will merely function as a lubricant, hence any freezing up or blocking of the mechanism which would permanently or even temporarily hinder operation can be quickly eliminated.

Another feature which is important and should be noted is the fact that the driving mechanism is placed and secured on top of the seats and as such permits an installation of this character to be placed in any standard life-boat without any change to the seats or the air tanks placed under the seats or alongside the same. Also all strains are carried by the seats and transmitted to the sides of the boat, hence danger of straining and opening the seams in the bottom of the boat is entirely avoided.

While this and other features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:—

1. A boat propelling device comprising reciprocal rods, supports for said rods fixed relative to said boat, cables operated by said rods, a plurality of handles on said rods, brackets fixed to said rods, guide pulleys for said cables rotatably mounted in said brackets, a guide rod fixed relative to said boat, and means on said brackets slidable on said guide rods whereby axial turning of said reciprocal rods is prevented.

2. In a propelling mechanism for a boat having thwarts, a power transmission device adapted to be secured in the boat and having a propeller shaft and motion transmitting connections geared thereto, including a pair of cables, a driving mechanism for exerting a reciprocal movement to said cables, said mechanism comprising a pair of reciprocal rods extending longitudinally substantially amidship of the boat and connected one with each cable, guide members for said reciprocal rods supported on said thwarts, a plurality of handles on each rod whereby the rods are grasped to exert an alternate push and pull to the rods to reciprocate the rods and connected cables, a cable connected at opposite ends of the rods, guide pulleys supported by said thwarts over which the intermediate portion of said cable travels to insure movement of the rods in opposition to each other when reciprocated, stationary guide rods mounted in the boat, a pair of brackets fixed one to each reciprocal rod and slidable on said stationary guide rods, said brackets supporting cable guide pulleys and carrying attaching means for said guide cable.

3. In a propelling mechanism for a boat having thwarts, a power transmission device adapted to be secured in the boat and having a propeller shaft and motion transmitting connections geared thereto, including a pair of cables, a driving mechanism for exerting a reciprocal movement to said cables, said mechanism comprising a pair of reciprocal rods extending longitudinally substantially amidship of the boat and connected one with each cable, guide members for said reciprocal rods supported by said thwarts, a plurality of handles on each rod whereby the rods are grasped to exert an alternate push and pull to the rods to reciprocate the rods and connected cables, a cable connected at opposite ends of the rods, guide pulleys supported by said thwarts over which the intermediate portion of said cable travels to insure movement of the rods in opposition to each other when reciprocated, stationary guide rods mounted in the boat, a pair of brackets fixed one to each reciprocal rod and slidable on said stationary guide rods, said brackets supporting cable guide pulleys and carrying attaching means for said guide cable.

3. In a propelling mechanism for a boat having thwarts, a power transmission device adapted to be secured in the boat and having a propeller shaft and motion transmitting connections geared thereto, including a pair of cables, a driving mechanism for exerting a reciprocal movement to said cables, said mechanism comprising a pair of reciprocal rods extending longitudinally substantially amidship of the boat and connected one with each cable, guide members for said reciprocal rods supported by said thwarts, a plurality of handles on each rod whereby the rods are grasped to exert an alternate push and pull to the rods to reciprocate the rods and connected cables, a cable connected at opposite ends of the rods, guide pulleys supported by said thwarts over which the intermediate portion of said cable travels to insure movement of the rods in opposition to each other when reciprocated, stationary guide rods mounted in the boat, a pair of brackets fixed one to each reciprocal rod and slidable on said stationary guide rods, said brackets supporting cable guide pulleys and carrying attaching means for said guide cable.

4. In a life boat propelling device, a pair of reciprocal rods, means on the thwarts of the boat forming supports and guides for said rods, a pair of cables attached at one end to a fixed support and at the opposite ends to a propelling mechanism, a pulley carried by each rod over which the respective cables pass whereby when the rods are reciprocated a pull is alternately exerted on each cable, and handles on the respective rods to impart reciprocal movement to the rods.

5. A boat propelling device comprising reciprocal rods, supports for said rods fixed relative to the boat, a plurality of handles on each rod to impart reciprocal movement thereto, a bracket on each rod, a pulley journaled in each bracket, and a pair of cables fixed at one end, said cables passing over the pulleys and returning back upon themselves and having their opposite ends attached to a propelling mechanism.

6. A boat propelling device comprising reciprocal rods, supports for said rods fixed relative to the boat, a plurality of handles on each rod to impart reciprocal movement thereto, a bracket on each rod, a pulley journaled in each bracket, a pair of cables fixed at one end, said cables passing over the pulleys and returning back upon themselves and having their opposite ends attached to a propelling mechanism, a guide rod fixed to each first-named rod and offset with relation thereto, and fixed guide members in the boat in which the guide rods are guided to prevent axial rotation of the first-named rods.

CLARENCE W. ALLEN.
